DESIGN FOR AN ENGINE CONTROLLING MECHANISM

Merton J. Smith, Cleveland, Ohio, assignor of twenty-five per cent to Paul B. Shannon, Chicago, Ill., twenty-five per cent to John Perry Geiger, Cleveland, Ohio, and twenty-five per cent to Robert W. Wilson, Rocky River, Ohio

Application June 24, 1942, Serial No. 107,337

Term of patent 7 years

To all whom it may concern:

Be it known that I, Merton J. Smith, a citizen of the United States and a resident of Cleveland, Cuyahoga County, Ohio, have invented a new, original, and ornamental Design for an Engine Controlling Mechanism, of which the following is a specification, reference being had to the accompanying drawings forming a part thereof.

In the drawings:

Fig. 1 is a plan view of an engine controlling mechanism showing my new design.

Fig. 2 is a front elevation;

Fig. 3 is a rear elevation;

Fig. 4 is an end elevation looking in the direction of the arrows 4—4, Fig. 2; and

Fig. 5 is an end elevation looking in the direction of the arrows 5—5, Fig. 2.

I claim:

The ornamental design for an engine controlling mechanism, as shown.

MERTON J. SMITH.
